BALLAST TAMPING MACHINE

Frank H. Philbrick, Chicago, Ill.

Application October 1, 1945, Serial No. 619,585

11. Claims. (Cl. 104—12)

1

The invention relates to ballast tamping machines and more particularly to the type which is adapted to pack the ballast under the ties.

One object of the invention is to provide a ballast tamping machine which includes means for positively controlling the movements of the tamping elements in paths for packing the ballast under the ties.

Another object of the invention is to provide a ballast tamping machine of the drop hammer type which includes elements for tamping the ballast under the ties and which includes means positively guiding the tamping elements in vertical paths at the sides of a tie and then in an arcuate path, to pack the ballast under the tie.

Another object of the invention is to provide a ballast tamping machine of the drop hammer type which is efficient in operation.

Other objects of the invention will appear from the detailed description.

The invention consists in the several features hereinafter set forth and more particularly defined by claims at the conclusion hereof.

In the drawings:

Fig. 1 is a plan view of a machine exemplifying the invention.

Fig. 2 is a longitudinal section of a portion of the frame, illustrating the tamping elements in their raised position.

Fig. 3 is a similar section illustrating the tamping elements in their dropped position.

Fig. 4 is a transverse section taken on line 4—4 of Fig. 2.

Fig. 5 is a perspective of the crosshead which functions as a drop hammer and carries the tamping elements.

Fig. 6 is a vertical section, illustrating the lifting mechanism for operating the crosshead.

Fig. 7 is a perspective of one of the link connections and rollers for co-acting with stationary cam tracks to control the path of movement of the tamping elements.

Fig. 8 is a perspective of the portion of the frame structure in which the crosshead is guided and the stationary cam-structure for guiding the tamping elements.

The machine of the invention is exemplified on a truck or car which comprises a truck-frame 10, which is supported on wheels 12 for traveling on the rails *a* of a railway track. An internal combustion motor 14 is mounted on frame 10 with the usual accessories and transmission for driving the truck-wheels 12, as well understood in the art.

The tamping elements are operable by a cross-

2

head, generally designated 16, which extends transversely of the truck and is mounted to slide vertically in channel-guides 18 which are fixedly supported on the frame 10. This crosshead carries the tamping elements and functions as a drop hammer for operating said elements to tamp the ballast under the ties *b* on which the rails *a* are laid. Guides 18 are fixedly secured to side-beams 11 of frame 10 through plates 20. The upper ends of guides 18 are rigidly cross-connected by channel beams 22 to provide a rigid structure in which the crosshead 16 is vertically slidable. The frame includes transverse beams 17 which are secured to side-beams 11 and are spaced apart for the operation between them of the crosshead 16 and the tamping elements.

Crosshead 16 is operable by power from the motor 14 through mechanism which lifts said crosshead and then releases it for a drop-hammer stroke. This mechanism comprises a transverse shaft 24 which is journaled in bearing brackets 26 which are supported on a cross-beam 28 of the frame structure and a sprocket wheel 30 fixed to shaft 24, which is driven by a chain 31 which is driven by suitable speed reducing mechanism from the motor 14. Intermittent movement is imparted to crosshead 16 from shaft 24 by a pair of link-chains 33, which are driven by sprockets 34 which are fixed to shaft 24. Chains 33 pass around lower idler sprockets 36. Rollers 38 carried by chains 33 are adapted to engage abutments 39 on one side of crosshead 16. Each idler sprocket 36 is preferably journaled on a lever 40 which is fulcrumed at 41 on one of the beams 17 and has connected thereto a spring 42 for maintaining its chain 33 taut. As the aligned rollers 38 on chains 33 during upward travel, engage the abutments 39, they will lift the crosshead 16 until said rollers in their travel around sprockets 34 release abutments 39 and permit crosshead 16 to drop and impart a hammer stroke to the tamping elements carried thereby, as hereinafter described. In this manner, the aligned rollers 38 on each chain 33 impart intermittent lifting strokes to crosshead 16. Crosshead 16 is provided with vertical grooves 44 for clearing the chains 33 during the dropping of said crosshead and with a vertical groove 45 for clearing the sprocket wheel 30 on shaft 24.

A gang of tamping elements or tools is provided at each side of crosshead 16. These elements are exemplified by shoes 46 which are provided with depending teeth 50. The elements of each gang are co-axially pivoted on pins 47, each of which is supported in a pair of ears 48 on the outer end

of an arm 49 which is integral with and on the lower end of the crosshead 16. The tamping elements of the gangs on opposite sides of the crosshead are disposed in opposed relation to one another and descend at the opposite sides of the tie b, to swing toward each other for packing the ballast between them under the tie. Teeth 50 are preferably curved inwardly to reach under the tie.

The invention includes mechanism for positively guiding the gangs of tamping elements on the opposite sides of the crosshead 16 to impart vertical movement to them while the teeth 50 on the opposed shoes 46 are above the ballast and to swing toward each other to tamp the ballast under the tie. Each shoe 46 is provided with an upstanding integral arm 52 at one side of the crosshead. The shoes 46 of each gang are connected for conjoint swinging movement by a cross-shaft 53. Each cross-shaft 53 is connected by a link 54 composed of two parallel members to a pivot pin 56 which is carried in the lower end of a pair of depending links 58, the upper ends of which are rigidly connected to a shaft 59 which is journaled in lugs 60 which are integral with crosshead 16. A roller 62 is journaled on each cross-shaft 53 and a roller 64 is journaled on each pin 56 between the members of link 54. The depending links 58 function as suspension links for pivot pins 56 and rollers 64. Links 54 function as connecting or thrust links between the suspension links 58 and rollers 64 and 62 on shaft 53. Links 54 and 58 operate as a toggle linkage between the arms 52 and crosshead 16.

The swinging movement of the gang of tamping elements is controlled by a single track-structure which is provided with rectilinear and cam members and which is stationarily supported on the supporting frame substantially at the transverse center of the crosshead. This structure includes inner and outer cams for engaging rollers 62 and 64, respectively, for both gangs of tamping elements. This cam-structure includes a post 66, the upper end of which is rigidly supported by brackets 67 which are secured between the upper beams 22 of the supporting frame structure. Post 66 extends through a vertical opening 68 in crosshead 16. The lower portion of post 66 is provided with downwardly divergent cams 69 for engaging rollers 64 which are supported by suspension links 58. Upstanding members 70, integral with and connected to the lower end of post 66 by a base member 71, are engaged by rollers 62 and the lower portions of said members are provided with downwardly divergent cams 74. The lower portion of the cam-structure is guided against transverse movement by guides 76 which are fixed to beams 17.

The cam-structure is vertically adjustable by means of rods 79 and nuts 80 for setting the entire cam structure into position for the operation of the tamping elements in the proper range for track rails of different heights. The cam-structure is locked in its adjusted position by set screws 72 which extend through channel-beams 22 and engage the open end of post 66. The inner cams 69 positively guide the rollers 62 to control the movements of teeth 50 on shoes 46 towards each other, and the cams 74 act on rollers 62 to spread apart the teeth 50 during the upward movement of the shoes 46. In this manner, the pivotal movement of the shoes is positively controlled in opposite directions. Cams 69 and 74 are usually set so that rollers 64 and 62 will be finally arrested by the ballast during the operative strokes 73

of the tamping elements, to avoid impact blows to the cam-structure.

The operation of the tamping mechanism will be as follows: the machine will be positioned on the track so that the tie under which the ballast is to be tamped will be positioned centrally below the crosshead and between the tamping elements on the opposite sides of the crosshead. Shaft 24 is continuously driven by motor 14 through chain 31 and sprocket 30. Shaft 24 drives sprockets 34 and chains 33 on said sprockets. Rollers 38 on chains 33 will intermittently engage abutments 39 and lift the crosshead 16 and the tamping mechanism until the rollers 38 pass off said abutments and release the crosshead which will drop the tamping devices. Upon release of the crosshead at the upper end of its stroke, tamping shoes 46 and teeth 50 will move vertically and rectilinearly while rollers 64 and 62 travel between the upper rectilinear members of the cam structure until the lower ends of the teeth reach approximately the top of the ballast. During the continued drop of crosshead 16, rollers 64 on the opposite sides of the crosshead will be shifted by cams 69 on post 66 to positively swing the shoes 46 so that points of teeth 50 of opposed gangs will swing toward each other and pack the ballast under the tie and between the teeth 50. During the upstrokes of the crosshead, the cams 74 will engage rollers 62 and positively swing the shoes in reverse direction to clear the ties. In this manner, during the rectilinear vertical movements of the crosshead the tamping shoes 46 and teeth 50 will be positively guided in a controlled path to pack the ballast under the tie and to withdraw said teeth from under the tie. The cam-structure and toggle-linkages positively control the path of movement of the tamping shoes and teeth to insure the packing of the ballast under the ties.

The invention exemplifies a machine of the drop-hammer type for tamping ballast under ties in which the pivotal movement of opposed tamping elements at opposite sides of the tie are positively controlled to cause the teeth to pack the ballast under the ties. The invention also exemplifies a machine of this type in which a single stationarily supported cam-structure controls the path of travel of gangs of tamping elements at the opposite sides of the crosshead.

The invention is not to be understood as limited to the details described, since these may be modified within the scope of the appended claims without departing from the spirit and scope of the invention.

Having thus described the invention, what I claim as new and desire to secure by Letters Patent is:

1. In a machine for tamping ballast in cribs between railway ties, the combination with a portable frame, a head mounted for substantially vertical sliding movement in the frame, mechanism for raising and lowering the head and tamping elements for the ballast in the cribs, fulcrumed at a fixed point on the head for vertical bodily movement and to swing transversely of the ties; of mechanism for controlling the pivotal movement of the tampers during the strokes of the head, comprising, an arm fixed to swing the tamping elements transversely of the ties on their fulcrum on the head, a vertically elongated track structure stationarily mounted on the portable frame, including rails with rectilinear and cam members, and means operatively connected to swing the arm and controlled by the rail members

5

for substantially vertical rectilinear and for pivotal movements of the tamping elements during the strokes of the head.

2. In a machine for tamping ballast in cribs between railway ties, the combination with a portable frame, a head mounted for substantially vertical sliding movement in the frame, mechanism for raising and lowering the head, and tamping elements for the ballast in the cribs fulcrumed at a fixed point on the head for vertical bodily movement and to swing transversely of the ties; of mechanism for controlling the pivotal movement of the tampers during the strokes of the head, comprising, an arm fixed to swing the tamping elements transversely of the ties on their fulcrum on the head, a vertically elongated track-structure stationarily mounted on the portable frame including substantially parallel rails with rectilinear and cam-members, and means operatively connected to swing the arm and controlled by the rail members for rectilinear movement of the elements during the upper portion, and for pivotal movement of the elements during the lower portion of the strokes of the head.

3. In a machine for tamping ballast in cribs between railway ties, the combination with a portable frame, a head mounted for substantially vertical sliding movement in the frame, mechanism for raising and lowering the head, and tamping elements for the ballast in the cribs fulcrumed at a fixed point on the head for vertical bodily movement and to swing transversely of the ties; of mechanism for controlling the pivotal movement of the tampers during the strokes of the head, comprising, an arm fixed to swing the tamping elements transversely of the ties on their fulcrum on the head, a vertically elongated track-structure stationarily mounted on and at substantially the transverse center of the portable frame including substantially parallel rails with rectilinear and cam members, and means operatively connected to the head for travel along the rails, operatively connected to swing the arm, and controlled by the rail members for rectilinear and pivotal movements of the elements during the strokes of the head.

4. In a machine for tamping ballast in cribs between railway ties, the combination with a portable frame, a head mounted for substantially vertical sliding movement in the frame, mechanism for raising and lowering the head, and tamping elements for the ballast in the cribs fulcrumed at a fixed point on the head for vertical bodily movement and to swing transversely of the ties; of mechanism for controlling the pivotal movement of the tampers during the strokes of the head, comprising, an arm fixed to swing the tamping elements transversely of the ties on their fulcrum on the head, a vertically elongated track-structure stationarily mounted on the portable frame including substantially parallel rails with rectilinear and cam members, and means operatively connected to the head for travel along the rails and including roller-means for travel along the rail-member and connected to rock said arm for rectilinear and pivotal movements of the elements during the strokes of the head.

5. In a machine for tamping ballast in cribs between railway ties, the combination with a portable frame, a head mounted for substantially vertical sliding movement in the frame, mechanism for imparting lifting strokes to the head and dropping it for hammer strokes, and tamping elements for the ballast in the cribs fulcrumed at a fixed point on the head for vertical bodily move-

6

ment and to swing transversely of the ties; of mechanism for controlling the pivotal movement of the tampers during the strokes of the head, comprising, an arm fixed to swing the tamping elements transversely of the ties on their fulcrum on the head, a vertically elongated track-structure stationarily mounted on the portable frame including substantially parallel rails with rectilinear and cam-members, and means including roller-means, a link connected to the head and to the roller-means for shifting the roller-means vertically, and a link connected to the roller-means and the arm for rocking the arm, when the roller-means engages the cam-members.

10 6. In a machine for tamping ballast in cribs between railway ties, the combination with a portable frame, a head mounted for substantially vertical sliding movement in the frame, mechanism for imparting lifting strokes to the head and dropping it for hammer strokes, and tamping elements for the ballast in the cribs fulcrumed at a fixed point on the head for vertical bodily movement and to swing transversely of the ties; of mechanism for controlling the pivotal movement of the tampers during the strokes of the head, comprising, an arm fixed to swing the tamping elements transversely of the ties on their fulcrum on the head, a vertically elongated track-structure stationarily mounted on the portable frame including substantially parallel rails with rectilinear and cam-members, and a post extending vertically through the head, and means operatively connected to swing the arm, and controlled by the rail members for rectilinear and pivotal movements of the elements during the strokes of the head.

20 7. In a machine for tamping ballast in cribs between railway ties, the combination with a portable frame, a head mounted for substantially vertical sliding movement in the frame, mechanism for imparting lifting strokes to the head and dropping it for hammer strokes, and tamping elements for the ballast in the cribs fulcrumed at fixed points on opposite sides of the head respectively, for vertical bodily movement and to swing transversely of the ties; of mechanism for controlling the pivotal movement of the tampers on the head, comprising, arms fixed to swing the tamping elements at the sides of the head respectively, a vertically extending track-structure stationarily mounted on the portable frame having a pair of substantially parallel rails at each side of the head, and means at each side of the head operatively connected to the head for travel along the rails and operatively connected to oppositely swing the arms and controlled by the rail members for rectilinear and pivotal movements of the tamping elements during the strokes of the head.

40 8. In a machine for tamping ballast in cribs between railway ties, the combination with a portable frame, a head mounted for substantially vertical sliding movement in the frame, mechanism for imparting lifting strokes to the head and dropping it for hammer strokes, and tamping elements for the ballast in the cribs fulcrumed at fixed points on opposite sides of the head respectively, for vertical bodily movement and to swing transversely of the ties; of mechanism for controlling the pivotal movement of the tampers comprising, arms fixed to swing the tamping elements at the sides of the head respectively, a vertically extending track structure stationarily mounted on the portable frame having a pair of

substantially parallel rails at each side of the head, and means at each side of the head operatively connected to the head for travel along the rails and operatively connected to oppositely swing the arms and controlled by the rail members for controlling the tamping elements to move rectilinearly during the upper portions and pivotally during the lower portions of the strokes of the head.

9. In a machine for tamping ballast in cribs between railway ties, the combination with a portable frame, a head mounted for substantially vertical sliding movement in the frame, mechanism for imparting lifting strokes to the head and dropping it for hammer strokes, and tamping elements for the ballast in the cribs fulcrumed at fixed points on opposite sides of the head respectively, for vertical bodily movement and to swing transversely of the ties; of mechanism for controlling the pivotal movement of the tampers comprising, arms fixed to swing the tamping elements at the sides of the head respectively, a vertically extending track-structure stationarily mounted on and substantially at the transverse center of the portable frame having a pair of substantially parallel rails at each side of the head, and means at each side of the head operatively connected to the head for travel along the rails and operatively connected to oppositely swing the arms and controlled by the rail members for rectilinear and pivotal movements of the tamping elements during different portions of the strokes of the head.

10. In a machine for tamping ballast in cribs between railway ties, the combination with a portable frame, a head mounted for substantially vertical sliding movement in the frame, mechanism for imparting lifting strokes to the head and dropping it for hammer strokes, and tamping elements for the ballast in the cribs fulcrumed at fixed points on opposite sides of the head respectively, for vertical bodily movement, and to swing transversely of the ties; of mechanism for controlling the pivotal movement of the tampers comprising, arms fixed to swing the tamping elements at the sides of the head respectively, a vertically extending track structure stationarily mounted on the portable frame having a pair of substantially parallel rails at each

5 side of the head, and means at each side of the head operatively connected to the head including roller-means for travelling along the rails and operatively connected to oppositely swing the arms and controlled by the rail members for rectilinear and pivotal movements of the tamping elements during different portions of the strokes of the head.

11. In a machine for tamping ballast in cribs between railway ties, the combination with a portable frame, a head mounted for substantially vertical sliding movement in the frame, mechanism for imparting lifting strokes to the head and dropping it for hammer strokes, and tamping elements for the ballast in the cribs fulcrumed at fixed points on opposite sides of the head respectively, for vertical bodily movement therewith, and to swing transversely of the ties; of mechanism for controlling the pivotal movement of the tampers comprising, arms fixed to swing the tamping elements at the sides of the head respectively, a vertically extending track structure stationarily mounted on the portable frame having a pair of substantially parallel inner and outer rails at each side of the head, rollers between the track-members, links operatively connected to the head for moving the rollers along the rails, and means at each side of the head including links controlled by the rollers and connected to oppositely swing the arms and controlled by the rail members for successive rectilinear and pivotal movements of the elements during the strokes of the head.
